UNITED STATES PATENT OFFICE.

OTTO H. HARTMANN, OF CASSEL-WILHELMSHOHE, GERMANY, ASSIGNOR TO
SCHMIDT'SCHE HEISSDAMPF-GESELLSCHAFT M. B. H., OF CASSEL-WIL-
HELMSHOHE, GERMANY, A CORPORATION OF GERMANY.

BOILER FOR MOVABLE STEAM-POWER PLANTS.

Application filed March 23, 1925, Serial No. 17,607, and in Germany April 2, 1924.

In locomotive boilers consisting of two parts working at different pressures, of which the high-pressure part is constructed as a fire-box and the low-pressure part as 5 a smoke-tube longitudinal boiler, only a very limited space is available for the fire-box in consequence of limitations imposed by the gauge of the railway. The high-pressure boiler, therefore, in boilers of the kind in 10 question heretofore proposed, contains only a small quantity of water and as a result when heavy demands for steam are made at high loads, priming frequently results.

According to the present invention, these 15 difficulties are overcome by extending the upper drum of the fire-box for a certain distance over the longitudinal boiler, the steam being preferably taken from the extension which thus serves as a steam collector.

This arrangement possesses, inter alia, the advantage that the high-pressure and the low-pressure boilers can be easily connected together so that the locomotive boiler, comprising two functionally distinct boilers, corresponds closely to the original Stephenson boiler which forms as it were the backbone of the whole locomotive.

In high-speed locomotives of high power 30 in which the longitudinal boiler is considerably raised, there is usually not sufficient space available above the longitudinal boiler for the upper drum of the fire-box.

In such a case, according to one form of 35 the present invention, the longitudinal boiler is recessed and the extension of the upper drum of the fire-box arranged in this recess. This construction makes it possible to give the upper drum of the fire-box the same 40 diameter over its entire length and thereby to secure an increase of water space.

In order to prevent priming, strainers, baffles or similar devices may be arranged 45 within the extended part of the upper drum of the fire-box, such part being thereby utilized as a separator for the water and steam.

In order to economize weight, the underlying idea of the present invention may be

developed as regards the structural connection of the two boilers. For example, the shell or wall of the high-pressure drum may serve likewise as the shell of the recessed part of the low-pressure boiler. As a result of this arrangement, a certain conduction of heat from the high-pressure boiler to the low-pressure boiler will result and no steam will therefore be produced from the water in the extension; on the contrary as the water in the extension is slightly cooled, it cannot become overheated in the region from which steam is taken, and such a boiler therefore supplies dry steam. This arrangement is of special importance in fire-box boilers which are heated indirectly by means of a heat-carrier (for instance water), the heat-transferrer in such a case being preferably arranged about the middle of the length of the upper drum leaving the ends unoccupied. In this way a water circulation from the middle towards the ends is established, whereby steam bubbles are separated and the supply of dry steam ensured.

The arrangements described above can be modified when desired by the application of 70 two upper drums arranged either on the longitudinal boiler or in recesses formed therein.

Illustrative forms of the invention are shown in the accompanying drawings:

Fig. 1 shows one form in longitudinal section,

Fig. 2 being a cross-section on the line 2-2 of Fig. 1;

Fig. 3 shows a second form in longitudinal section, while

Fig. 4 shows a similar view of a third form,

Fig. 5 being a cross-section on the line 5-5 of Fig. 4, and

Fig. 6 a similar section of a modification; finally

Fig. 7 shows in cross-section a method of structurally connecting the high-pressure and low-pressure boilers.

The fire-box of the locomotive is formed by water tubes, *a*, which extend upwardly

from lower water headers, *b*, to the steam-and-water drum, *c*. The longitudinal smoke-tube boiler is indicated by the letter, *d*. As above mentioned, the water-tube fire-box serving as the high-pressure boiler, can be provided with one or more upper steam-and-water drums.

In the form of the invention shown in Figs. 1 and 2, that part of the drum, *c*, which extends in a longitudinal direction over the longitudinal boiler is of less cross-sectional area than the remainder.

In the form of the invention shown in Figs. 3 to 7, the drum, *c*, has the same diameter throughout its entire length.

If the longitudinal boiler, as in the case of high speed engines of large power, is arranged with its centre of gravity at a considerable height, the space available would not be sufficient for accommodating the projecting part of the drum, *c*. As described above, the projecting part may, therefore, have a smaller diameter or, to avoid this, the longitudinal boiler, *d*, itself at its rear end may have a smaller cross-section than at the other parts of its length. There will thus be a depression or recess at this end of the boiler in which the upper drum can lie as shown in Figs. 3 to 7.

In the form of the invention shown in Fig. 4, the arrangement is such that the shell or wall of the projecting end of the drum, *c*, is common to the high-pressure boiler and to the longitudinal boiler, *d*, this arrangement having advantages which have already been explained above.

The forms of the invention shown in cross-section in Figs. 5 and 6 differ only in the fact that in Fig. 5 one drum, and in Fig. 6 two drums, *c*, are provided for the high-pressure boiler.

In all the examples shown in Figs. 3 to 7, the drums *c*, are connected rigidly with the longitudinal boiler in the region where they overlap one another. This connection can be effected in different ways. In Fig. 3, rings or straps, *e*, are arranged round the drum, *c*, and secured in any suitable way to the longitudinal boiler, *d*. In Fig. 7 the rigid connection of the parts in question is effected by arranging bearing brackets, *f*, on the drum, *c*, which are secured to the longitudinal boiler, *d*, by bolts or in any other suitable manner.

As described above, it is desirable to utilise the forwardly-extending end of the drum, *c*, of the high-pressure boiler as a dome and in this space, therefore, arrangements for separating the water and steam are preferably provided.

As an example of an arrangement suitable for this purpose, I have illustrated a screen or perforated baffle *h* in Figs. 1, 3 and 4.

It may also be pointed out that in Fig.

3, the generation of steam in the water-tube fire-box is effected through indirect heating of the water in the drum by means of a heat-carrier circulating in a closed circuit, the heat-transferrers, *g*, necessary for this purpose being preferably arranged at about the middle of the length of the drum so that a water circulation is established from this central region to the two ends.

The heat-carrier may be a fluid such as water, which would become heated in the header *b* and chiefly in the water tubes *a*, this heat carrier then rising into the heat-transferrer *g* which may be a set of pipes located within the drum *c*. The interior of these pipes does not communicate with the interior of the drum, but only with the tubes *a* and header *b*, so that the water forming the heat-carrier or heating medium will circulate through a closed path which has no communication with the drum *c*, but extends through said drum in heat-exchange relation to the water contained in said drum, to convert this water into steam.

In all the other forms of my invention illustrated herein, the water-space of the drum *c* communicates with the tubes *a*, so that steam is generated by direct heating, from the body of water contained in the header *b*, tubes *a*, and drum *c*. The indirect heating indicated in Fig. 3 requires two separate bodies of water, one of them circulating through a closed path *b*, *a*, *g*, and the other yielding the steam which is taken from the drum *c* to the place of use.

What I claim is:

1. A boiler for movable steam plants comprising a high pressure portion including a fire box having a drum for water and steam, and a low pressure portion arranged as a longitudinal boiler out of communication with the high pressure portion, the said low pressure boiler communicating with the fire box so as to be directly heated by the combustion products thereof, said steam and water drum projecting forwardly beyond the front of the fire box and above the rear portion of the longitudinal boiler so as to overlap the same, one of said overlapping parts being of smaller cross section at the overlapping portion than on the remaining portion of said part.

2. A boiler for movable steam plants comprising a high pressure portion including a fire box having a drum for water and steam, and a low pressure portion arranged as a longitudinal boiler out of communication with the high pressure portion, the said low pressure boiler communicating with the fire box so as to be directly heated by the combustion products thereof, said low pressure boiler portion being for a part of its length of smaller cross section than the remaining part, said steam and water drum projecting

forwardly beyond the front of the fire box above the smaller portion of the low pressure boiler portion.

3. In a boiler as claimed in claim 1, a rigid connection for connecting the overlapping ends of the drum and the low pressure boiler.

4. In a boiler as claimed in claim 1, water-separating devices arranged in the forwardly projecting part of the drum. 10

In testimony whereof I have hereunto set my hand.

OTTO H. HARTMANN.
